CLINKER SHELF

Ina L. Meilleur and Joseph Meilleur,
Spokane, Wash.

Application January 4, 1949, Serial No. 69,188

4 Claims. (Cl. 126—242)

1

This invention relates to coal burning furnaces and more particularly to a shelf which is mounted in a firebox of a furnace and upon which clinkers may be deposited while cooling.

When a coal burning furnace is in use the coal often forms clinkers which must be removed from the mass of burning coal, and if the clinkers are withdrawn from the fire box and drop upon the floor of a furnace room they emit smoke and fumes which are objectionable and liable to endanger the health of a person having charge of the furnace.

Therefore it is one object of the invention to provide a shelf which is mounted in the fire box of a furnace and thus allow clinkers to be removed from the burning coal and placed upon the shelf where they will remain until cool and all smoke and fumes given off by the clinkers pass from the furnace into the smoke pipe to the chimney instead of filling the furnace room with smoke and gases.

Another object of the invention is to provide a clinker shelf of such formation that it will extend circumferentially of the fire box and close to the annular wall thereof where it will be out of the way and not interfere with operation of the furnace.

Another object of the invention is to provide a clinker shelf which may be supported upon a ledge formed by the upper edge face of the fire box wall where it will remain firmly in place and not be liable to tilt over and drop into the fire.

Another object of the invention is to provide a clinker shelf which is formed of cast iron and so reinforced that it will not become warped by heat from the fire.

Another object of the invention is to provide a clinker shelf which is formed as a single casting and may be manufactured at low cost.

The invention is illustrated in the accompanying drawings wherein:

Fig. 1 is a view taken horizontally through a furnace and showing the improved clinker shelf in top plan.

Fig. 2 is a sectional view upon an enlarged scale taken along the line 2—2 of Figure 1.

Fig. 3 is a perspective view looking at the under face of the clinker shelf.

The furnace in which the improved clinker shelf is mounted is of conventional form and has the usual fire box 1 and head 2. The fire box has at the center of its bottom a fuel bowl or tuyère 3 of conventional form and about its upper edge face the fire box is formed with an outstanding circumferentially extending flange

2

or thickened portion 4 there is a groove 5 in which is seated the lower edge portion of the head 2. The inner surface of the head is spaced from the inner surface of the fire box, thus providing a rim or ledge 6 which extends circumferentially about the fire box within the bottom or lower end of the head. The furnace is therefore of conventional formation and will include the usual doors for the fire box and the ash pit.

10 The clinker shelf 7 which constitutes the subject matter of this invention is formed of cast iron and has arcuate inner and outer side edges 8 and 9 and straight cut ends 10 which are in alignment with each other, as shown in Figure 1. Short legs 11 extend downwardly from the outer side edge of the shelf in spaced relation to each other longitudinally thereof, and each leg has a vertically arcuate outer edge face 12 and its upper portion outwardly thickened to form 15 a lug or shoulder 13 formed with a flat and straight under face which rests flat upon the rim or ledge 6 of the fire box when the shelf is applied to the fire box. Since the outer faces of the legs are longitudinally curved the legs diverge 20 downwardly from the wall of the fire box and will not be liable to catch against the inner face of the fire box and prevent the shelf from being easily set in place within the fire box. Openings 14 are formed through the shelf so that hot air, smoke, and other products of combustion rising from a fire under the shelf may pass 25 through these openings and in order to brace the shelf against warping there has been provided a rib 15 which is formed integral with the shelf and extends from the center one of the legs 11 to the inner side edge of the shelf.

When the clinker shelf is in use it is thrust into the fire box through the fuel door and set at rest upon the rim or ledge 6 with the shoulders or lugs 13 of the legs resting upon the rim and upper ends of the arcuate side faces 12 of the legs bearing against the inner surface of the wall of the fire box. Since the lugs 13 project outwardly from the outer side face 9 of the shelf a short distance the shelf will be held in spaced relation to the walls of the fire box and the heat and air may flow upwardly about the outer side edge of the shelf as well as through the draft openings 14. When it is found that coal burning in the fire box contains clinkers, the clinkers are removed from the coal and placed upon the shelf where they are allowed to remain until they are cool. Smoke and gas fumes given off by the cooling clinkers will thus be in the furnace 30 and pass out through the smoke pipe instead of

filling the furnace room with smoke and obnoxious gases, as would be the case if the hot clinkers were withdrawn through the fuel door and allowed to drop upon the floor of the furnace room.

Having thus described the invention, what is claimed is:

1. A clinker shelf adapted for use in a furnace having a fire box and a head resting upon the upper edge face of the wall of the fire box, said shelf comprising a flat body having arcuate inner and outer side edges and straight end edges extending between ends of the inner and outer side edges, said body being formed with openings constituting passages for products of combustion moving upwardly in the fire box from burning coal under the shelf, short legs extending downwardly from the outer side edge portion of said body and spaced from each other longitudinally thereof, said legs having vertically arcuate outer side faces and having their upper portions outwardly thickened and forming shoulders projecting from the outer side edge of the body radially thereof and formed with flat lower end faces for resting upon the upper edge face of the wall of the fire box wall and supporting the clinker shelf in the fire box of a furnace above a mass of coal therein with the body spaced from the wall of the head of the furnace, and a reinforcing rib extending across the under face of the body midway the length thereof between inner and outer side edges of the body.

2. A clinker shelf adapted for use in a furnace having a fire box and a head resting upon the upper edge face of the wall of the fire box, said shelf comprising a flat cast metal body having inner and outer side edges, said body being formed with a plurality of openings constituting passages for products of combustion moving upwardly in the fire box from burning coal under the shelf, legs formed integral with said body and spaced from each other along the outer side edge of the body, said legs having upper portions formed with outstanding lugs forming shoulders for resting upon a ledge in a fire box of the furnace and supporting the shelf in the furnace above burning coal in the fire box, and a rib formed integral with the body and extending across the under face of the body between inner and outer side edges thereof to reinforce the body against warping.

3. In combination with a furnace including a fire box open at its top and a head open at its

lower end and resting upon the upper edge of the wall of the fire box with portions of the fire box wall projecting inwardly from the head and forming a ledge surrounded by the lower end of the head; a clinker shelf comprising a body disposed horizontally and having an outer edge disposed over a portion of said ledge and an inner edge spaced laterally from the vertical center of the fire box, and legs extending downwardly from the outer edge portion of said body in spaced relation to each other longitudinally thereof and formed with shoulders resting upon the ledge and supporting the shelf above burning coal in the fire box, said legs having portions extending downwardly below the ledge and bearing against the inner surface of the wall of the fire box and bracing the shelf against tilting movement off of the ledge.

4. In combination with a furnace including a fire box open at its top and a head open at its lower end and resting upon the upper edge of the wall of the fire box with portions of the fire box wall projecting inwardly from the head and forming a ledge; a clinker shelf comprising a body disposed horizontally adjacent the wall of the head and having an outer edge portion disposed over said ledge, and supporting means extending downwardly from the outer edge portion of said body and having portions resting upon said ledge and removably mounting the clinker shelf above coal in the fire box and other portions extending downwardly below the ledge and bearing against the inner surface of the wall of the fire box and serving to brace the shelf against tilting movement off of the ledge.
